UNITED STATES PATENT OFFICE.

GEORGE A. LONG, OF SCRANTON, PENNSYLVANIA.

RAIL-JOINT.

1,132,367.

Specification of Letters Patent. Patented Mar. 16, 1915.

Application filed December 24, 1914. Serial No. 878,897.

To all whom it may concern:

Be it known that I, GEORGE A. LONG, a citizen of the United States, residing at Scranton, in the county of Lackawanna and State of Pennsylvania, have invented a new and useful Rail-Joint, of which the following is a specification.

The invention relates to improvements in rail joints.

The object of the present invention is to improve the construction of rail joints and to provide a simple, inexpensive, and efficient rail joint of strong and durable construction, equipped with rail bracing and clamping members capable of being firmly wedged against the rails and adapted when released to be readily removed from either end of the chair of the rail joint.

A further object of the invention is to provide a rail joint of this character having wedges arranged to be driven downwardly into the rail joint for forcing the rail clamping and bracing members against the rails and adapted to be easily withdrawn when it is desired to remove or adjust the said rails.

With these and other objects in view the invention consists of the construction and novel combination of parts hereinafter fully described, illustrated in the accompanying drawing, and pointed out in the claims hereto appended, it being understood that various changes in the form, proportion, size and minor details of construction, within the scope of the claims, may be resorted to without departing from the spirit or sacrificing any of the advantages of the invention.

In the drawing:—Figure 1 is a perspective view of a rail joint constructed in accordance with this invention. Fig. 2 is a transverse sectional view of the same. Fig. 3 is a perspective view of the rail chair. Fig. 4 is a perspective view of one of the rail bracing and clamping members. Fig. 5 is a similar view of one of the wedges.

Like numerals of reference designate corresponding parts in all the figures of the drawing.

In the accompanying drawing, in which is illustrated the preferred embodiment of the invention, 1 designates a rail chair consisting of a bottom plate 2 and spaced upwardly extending side flanges 3 formed integral with the bottom plate and located adjacent to the side edges thereof, the bottom

plate being extended beyond the flanges 3 to provide attaching portions 4 which have openings for the reception of spikes or other suitable fastening devices for securing the chair to the cross ties (not shown). The bottom plate 2, which has flat upper and lower faces, forms a seat 5 for the adjacent ends of the rails 6, which are arranged upon the intermediate connecting portion of the bottom plate between the upwardly extending side flanges 3. The side flanges 3 are provided with inner faces consisting of lower vertical portions 7 to fit against the side edges of the bottom flanges of the rails, 70 curved shoulders 8, and straight upwardly and inwardly extending inclined upper portions 9. The curved shoulders 8 extend upwardly and outwardly from the straight lower vertical portions 7, and are arranged 75 to receive and support rounded lower outer edges 10 of angle bracing and clamping members 11, consisting of outwardly extending bottom portions 12 and inner upwardly extending tapered portions 13. The 80 angle rail clamping and bracing members 11 fit against the upper faces of the bottom flanges of the rails and engage under the heads thereof, and the outer faces 14 of the bottom portions 12 are inclined upwardly 85 and inwardly to conform to the configuration of the upper portions 9 of the side flanges 3 of the chair. The inwardly extending upper portions of the flanges 3 and the inclined or beveled faces 14 of the 90 clamping and bracing members 11 form an interlocking connection, and the said members are of uniform cross-sectional area throughout their entire length to enable them, when released by the removal of the 95 wedges 15, to be readily removed from the chair at either end thereof. The upper faces of the flanges 3 and the upper faces of the bottom outwardly extending portions 12 of the clamping and bracing members 11 are 100 preferably arranged in flush relation, as shown, and the flanges and the members are provided with registering recesses 16 and 17, forming openings to receive the wedges 15, which are adapted to be driven downwardly through the rail joint to force the bracing and clamping members into tight engagement with the rails. One or more wedges may be employed at each side of the rail joint, as desired, and as the wedges are 110 vertically disposed, the bracing and clamping members may be easily forced into en-

gagement with the rails by simply driving the wedges downwardly. The wedges, which have heads 18 at their upper ends, are preferably provided below the same with transverse perforations for the reception of pins 19 adapted to project beyond the inner and outer sides of the wedges to facilitate the removal of the same when it is desired to change or adjust the rails. The 10 wedges, which have straight vertical edges, fit against the side edges of the recesses 16 and 17 and thereby interlock the clamping and bracing members against longitudinal movement. When the rails are clamped by 15 the members 11, they are securely held and firmly braced and the rail joint, which is adapted to receive ordinary rails, does not require notching or otherwise altering the construction of the same.

20 What is claimed is:—

1. A rail joint including a rail chair consisting of a bottom plate having a horizontal upper face to form a rail receiving seat, and spaced upwardly extending side flanges 25 provided with inner faces consisting of lower vertical portions to fit against the side edges of the bottom flanges of the rails, curved shoulders extending upwardly and outwardly from the said lower vertical portions, and upper inclined portions extending upwardly and inwardly from the said shoulders, angle rail bracing and clamping members arranged upon the bottom flanges and engaging under the heads of the rails 30 and having lower rounded outer edges, fitting the said shoulders of the side flanges of the chair, said members being provided with upwardly and inwardly inclined outer faces conforming to the inclined upper portions 35 of the inner faces of the said flanges to form an interlocking connection between the members and the chair, and approximately vertical wedges extending through the chair and interposed between the flanges of the 40 same and the said members, whereby the said members are wedged tightly against the 45

rails, said members being of uniform cross-sectional area and adapted, when released by the removal of the wedges, to be removed from either end of the rail chair. 50

2. A rail joint including a rail chair consisting of a bottom plate having a horizontal upper face to form a rail receiving seat, and spaced upwardly extending side flanges 55 provided with inner faces consisting of lower substantially vertical portions to fit against the side edges of the bottom flanges of the rails, shoulders extending upwardly and outwardly from the said lower vertical portions, and upper inclined portions extending upwardly and inwardly from the said shoulders, angle rail bracing and clamping members arranged upon the bottom flanges and engaging under the heads 60 of the rails and having lower edges fitting the said shoulders of the side flanges of the chair, said members being provided with upwardly and inwardly inclined outer faces conforming to the inclined upper portions of the inner faces of the said flanges to 65 form an interlocking connection between the members and the chair, said members and flanges being provided with registering recesses forming vertical openings which extend through the bottom of the rail chair, 70 and substantially vertical wedges arranged in the said recesses and adapted to be driven through the chair to wedge the members tightly against the rails, said wedges interlocking the members against longitudinal 75 movement and the members being of uniform cross-sectional area to enable them to be removed from either end of the chair when released by the wedges.

In testimony, that I claim the foregoing 85 as my own, I have hereto affixed my signature in the presence of two witnesses.

GEORGE A. LONG.
